W. F. O'ROURKE.
SASH FASTENING DEVICE.
APPLICATION FILED JUNE 14, 1906.

984,594.

Patented Feb. 21, 1911.

UNITED STATES PATENT OFFICE.

WILLIAM F. O'ROURKE, OF CHICAGO, ILLINOIS.

SASH-FASTENING DEVICE.

984,594.

Specification of Letters Patent. Patented Feb. 21, 1911.

Application filed June 14, 1906. Serial No. 321,655.

To all whom it may concern:

Be it known that I, WILLIAM F. O'ROURKE, citizen of the United States, residing at Chicago, in the county of Cook 5 and State of Illinois, have invented a certain new and useful Improvement in Sash-Fastening Devices, of which the following is a full, clear, concise, and exact description.

10 My invention relates to a fastening device, more particularly for hinged swinging windows, such as ordinary basement windows; and its object is to provide an improved, simple, strong and effective device 15 by which a window or the like may be securely supported and rigidly held in any position to which it may be swung, throughout a wide arc of movement.

I will describe my invention particularly 20 by reference to the accompanying drawing, in which,

Figure 1 is a vertical sectional view of a window or casing, hinged at the bottom, to which my improved support and fastening 25 device is applied; Fig. 2 is a front view of the locking member and the sliding brace rod coöperating therewith; Fig. 3 is a sectional side view of the locking member and rod shown in Fig. 2; Fig. 4 is a front view 30 of the pivoted fulcrum piece for said brace rod, and Fig. 5 is a sectional side view on line 5—5 of Fig. 4.

The same letters of reference indicate the same parts wherever they are shown.

35 In the drawing the invention is shown as applied to a basement window or casing *a* which is hinged at the lower edge *a*¹ to the casement or transom. The brace rod *b* is pivoted at the bottom to a fulcrum piece *f*, 40 the base-plate *f*¹ whereof is secured to the window-sill; and the upper portion of said brace rod is arranged to slide to and fro in a gripping member *c* which has a hinged connection with the upper portion of the window 45 casing or sash.

The gripping member is preferably constructed as shown, having a supporting frame *c*¹ with guide-wings *c*² *c*² having holes therein through which the brace-rod is 50 passed, and clutch members comprising gripper levers *d* *d* pivoted to the frame *c*¹ inside said guide-wings, said gripper levers also having holes through which the brace-rod is passed. The gripper levers are yieldingly held in an angular position by springs 55 *s* *s*, so that the rod is securely held locked

to the gripping member; but by grasping the gripper levers the rod may be released and adjusted to any desired position, the projecting ends of said levers constituting 60 means for releasing the clutch members from locking engagement with the brace rod. The yoke portion *c*³ of the frame *c*¹ constitutes means for limiting the movement of the gripping levers *d*, *d*. The 65 frame of the gripping member is hinged to a fastening plate *e* which has screw-holes therein, to be secured to the window sash.

Preferably the base plate *f*¹ of the fulcrum piece *f* is pivoted to said fulcrum piece 70 on an axis perpendicular to the plane of said base plate, so that the base plate may be turned to any angular position to fit in different positions upon the window-frame and to allow the brace-rod to accommodate 75 itself to varying angles.

The operation of the device will be apparent. To adjust the window in any position it is merely necessary to grasp the gripper levers and release the rod so that it is 80 free to slide, then swing the window to the desired angle and release the gripper levers, whereupon the rod will again be firmly locked, and the window thereby securely held and braced in its adjusted position. 85

I claim:—

1. The combination with a swinging window, of a rod pivotally supported at one end and extending in the same general direction as the window but at a slight inclination thereto to form a brace, and a locking member secured to the window and having sliding engagement with the free end of said rod, said locking member having means for gripping said rod. 90

2. The combination with a window having a hinge at its lower edge about which the window swings, of a brace rod hinged at its lower end at a slight distance from said hinge and extending to approximately 100 the upper edge of the window, and a locking member hinged upon the upper part of the window and having an adjustable locking engagement with said brace rod. 95

3. In a rod-fastening device, the combination with the gripper levers having holes through which the rod passes, of the supporting frame for said gripper levers, spring means for holding said gripper levers normally turned angularly to grip the rod, 110 guiding wings on said supporting frame outside said gripper levers, said wings

having alined guide-holes therein through which said rod passes, whereby the rod is held against rocking relatively to said supporting frame, and a fastening-plate hinged 5 to said supporting frame.

4. In a clutch for transom rods, the combination of a casing connected with the transom and engaged with the rod, said casing being arranged for movement with 10 respect to the latter and to said transom; a clutch member carried by the casing and yieldingly engaged with said rod; and means for releasing said member from such engagement.

15 5. In a clutch for transom rods, the combination of a rocking casing connected with the transom and arranged for movement upon the rod; a shiftable clutch member carried by the casing and yieldingly engaged with said rod; and means for releasing 20 said member from such engagement.

6. In a clutch for transom rods, the combination of a casing slidably mounted upon the rod and pivotally connected with the

transom; a clutch member disposed within 25 the casing and formed with a perforation through which said rod extends; means for normally holding said member in position to engage said rod with one end of its perforation; and means for releasing said member from such engagement.

7. In a clutch for transom rods, the combination of a rocking casing connected with the transom and arranged for movement upon the rod; a shiftable clutch member 35 carried by the casing and yieldingly engaged with said rod; means for shifting said member to release the same from such engagement; and means for limiting such movement.

In witness whereof, I hereunto subscribe my name this fourth day of June, A. D., 1906.

WILLIAM F. O'ROURKE.

Witnesses:

ALFRED H. MOORE,
D. C. TANNER.
